UNITED STATES PATENT OFFICE.

PHILIP PRINGLE, OF LIPTON, CANADA.

INTERNAL-COMBUSTION ENGINE.

1,140,394.

Specification of Letters Patent. Patented May 25, 1915.

Application filed May 27, 1914. Serial No. 841,345.

To all whom it may concern:

Be it known that I, PHILIP PRINGLE, of the town of Lipton, in the Province of Saskatchewan, Canada, have invented certain new and useful Improvements in Internal-Combustion Engines, of which the following is the specification.

The invention relates to improvements in internal combustion engines and the object of the invention is to provide a two cycle combustion engine having very efficient scavenging of the spent gases and one in which a variable control of the exhaust ports is supplied whereby the said exhaust ports can be closed at an earlier or later time during the stroke and complete cut off can be effected in varying positions of the piston.

A further object of the invention is to provide an inexpensive, easily operated and easily assembled engine of the above class.

With the above objects in view the invention consists essentially in the arrangement and construction of parts hereinafter more particularly described and later pointed out in the appended claims.

Figure 1 represents a side view of the engine, the crank case being shown in vertical section. Fig. 2 represents a vertical sectional view longitudinally through the engine, certain parts being shown in side elevation and the valves appearing in the position assumed when the piston is at the outer end of its stroke. Fig. 3 represents a longitudinal sectional view similar to Fig. 2 with the valves shown in the positions which they assume when the piston is at the inner end of its stroke. Fig. 4 represents a perspective view of the outer or long valve sleeve. Fig. 5 represents a perspective view of the inner or shorter valve sleeve. Fig. 6 represents a side view, part in section of the eccentrics and adjoining links controlling the outer sleeve, the parts being shown in a reverse position to that appearing in Fig. 1. Fig. 7 is an enlarged detailed horizontal sectional view through the cylinder, the section being taken in the plane denoted by the line P—P' Fig. 2. Fig. 8 is an enlarged detailed horizontal sectional view through the cylinder, the section being taken in the plane denoted by the line T—T' Fig. 2. Fig. 9 is an enlarged detailed horizontal sectional

view through the cylinder, the section being taken in the plane denoted by the line X—X' Fig. 2. Fig. 10 is an enlarged detailed horizontal sectional view through the cylinder, the section being taken in the plane denoted by the line Y—Y' Fig. 2. Fig. 11 is an enlarged detailed horizontal sectional view through the crank case, the section being taken in the plane denoted by the line Z—Z' Fig. 2, and looking toward the cylinder. Fig. 12 represents diagrammatically an enlarged detailed side view of the eccentrics and crank.

In the drawings like characters of reference indicate corresponding parts in each figure.

1 represents the crank case fitted with hangers 2 and 3 whereby the case can be suitably suspended from an adjoining structure. 4 represents the drive shaft of the engine mounted in suitable bearings presented by the crank case and fitted more or less centrally with a crank 5. 6 represents the engine cylinder which is suitably water jacketed as indicated at 7 and has the lower end flared outwardly at 8 and fastened by bolts 9 to the crank case, the bolts passing through the cylinder head 10 and effecting the fastening of the head to the cylinder as will readily be understood. The head is supplied with a central boss 11 and a short sleeve 12, the boss and sleeve being preferably cast integral with the head and arranged so that they extend within and are concentric with the cylinder when the said parts are assembled. The upper end of the cylinder is water jacketed and carries a spark plug 14 and an oil nozzle 15. These parts are simply indicated in the drawing as their details of construction are well known and form no part of the present invention.

In actual practice a small suitably driven oil pump (not shown) is utilized to inject the proper amount of oil through the nozzle into the interior of the cylinder and the pump is controlled by a governor so that the proper amount of oil will be injected under the various running conditions. I wish it to be here noticed that the lower end of the cylinder is of a somewhat larger bore than the upper end, the change in internal diameter appearing at the shoulder 16. The rea-

son for this will be later explained. The lower end of the cylinder is supplied with a plurality of circumferentially arranged air inlet openings 17 and the upper end is supplied with a plurality of circumferentially arranged exhaust ports 18 which communicate directly with the exhaust manifolds 19 and 20. These manifolds can be connected to suitable exhaust pipes.

21 represents a long or outer valve sleeve slidably received within the cylinder and provided more or less centrally of its length with a comparatively thick wall in which I have formed a plurality of transfer slots 22, 25 the said slots actually appearing in the inner wall of the sleeve. As will be noticed the upper or contracted portion of the sleeve fits into the contracted or smaller end of the cylinder while the enlarged end of the sleeve is received slidably within the enlarged or lower end of the cylinder.

23 is a shank extending from the lower end of the sleeve through the head 10 and operating between suitable guides 24 extending from the under side of the head.

25 are elongated air inlet openings located in the lower end of the sleeve and 26 are exhaust ports located in the upper end of the cylinder, the said inlet openings and ports 30 being arranged to sweep over and register with the former air inlet openings 17 and the exhaust ports 18 at proper instances as later described.

27 is a short or inner sleeve received slidably within the lower end of the outer sleeve and enveloping also the sleeve 12 of the head. The inner sleeve is supplied also with an extending shank 28 which projects through the head 10 and operates between 40 suitable guides 29 cast on the under side of the head. The inner sleeve is supplied with a plurality of circumferentially arranged air inlet openings 30 which control the entrance of fresh air to the lower end of the cylinder 45 as later described.

31 is a piston slidably mounted in the upper or contracted end of the inner sleeve. The flange 32 of the piston is designed so that it is spanned by the transfer slots when 50 withdrawn to the position shown in Fig. 2 of the drawing that is to the outer end of the stroke.

33 is a piston rod slidably mounted in the boss and having the upper end connected to the piston and the lower end connected to a cross head 34 located between suitable cross head guides 35 and 36 cast on the under side of the head 10.

37 is a connecting rod carried by the crank 60 5 and having the upper end connected to the cross head by means of a pin 38.

39, 40 and 41 are eccentrics permanently mounted on the crank shaft, the eccentrics 39 and 40 being utilized to effect a varying

control of the outer sleeve while the eccentric 41 effects the constant control of the inner sliding sleeve.

42 is a link connected by a pin 43 to the shank 28 and by an eccentric strap 44 to the eccentric 41. The forward end of the shank 70 23 is forked and carries a pin 45 on which I have mounted a square block 46 received slidably within a rectangular frame 47, the one end of the frame being connected by a pin 48 with the link 49 passing to an eccentric strap 50 mounted on the cam 40 while the other end is connected by means of a pin 51 with a link 52 passing to an eccentric strap 53 mounted on the eccentric 39.

54 is a cross shaft suitably mounted in 80 the crank case and fitted with a lever 55 and a crank 56, the crank being connected by means of a link 57 with the frame 47. Suitable means are provided whereby the lever can be adjusted and retained in any adjusted 85 position.

With the construction just described it will be seen that by throwing the lever one can manipulate the frame so that the links 49 and 52 can be adjusted in respect to the 90 shank.

In the position shown in Fig. 1 of the drawing it is obvious that the eccentric 40 will control the shank 23 and consequently the outer sleeve as the connection of the cam 95 39 will be simply taken up in a rocking motion produced in the frame. On the other hand it will be seen that if the lever be thrown to a position which will place the frame in the position shown in Fig. 6 of the 100 drawing the shank 23 and consequently the outer sleeve will be controlled in its movement by the eccentric 39, the action of the cam 40 at this time being taken up in a rocking motion produced in the frame through 105 the link 49. In the intermediate positions of the lever the shank will be controlled by either one or other of the cams.

In order to better understand the invention I have considered it best to show diagrammatically in Fig. 12 the actual positions of the eccentrics in which said figure I have indicated the centers of the several eccentrics by the reference numerals "a", "b" and "c" and the center point of the crank 115 by the reference numeral "d". The axis of the drive shaft is indicated by the reference letter "e". Upon examination of the figure it will be found that the throw of the eccentric 40 is greater than the throw of the eccentric 41 and that the throw of the eccentric 39 is less than either of the other two. Further it will be seen that both of the eccentrics 39 and 40 are behind the crank while the eccentric 41 is in advance thereof.

In actual design the eccentric 39 is thirty-five degrees and the eccentric 40 five degrees behind the crank while the eccentric 41 is

sixty five degrees in advance of the crank. With the eccentrics in these positions in respect to the crank and the crank in the position shown in Fig. 3 of the drawings it will be noticed that the piston is at the inner end of the stroke, the exhaust ports are closed and the air inlet ports are about to close. With the piston in this position and the previously introduced charge exploded 10 the operation is as now described: As the piston passes down on the working or out stroke, the air previously admitted to the interior of the cylinder beneath the piston is compressed, the air inlet ports being maintained closed. Prior to the piston reaching the transfer slots and being spanned by them the exhaust ports 26 open to the exhaust ports 18 so that the instant the slots are opened the spent gases are effectively 20 scavenged by the compressed air escaping around the piston through the slots and into the upper end of the cylinder.

I wish here to emphasize the fact that the exhaust ports open prior to the scavenging. 25 Actually the air is admitted into the upper end of the cylinder approximately ten degrees after the exhaust ports have opened. The scavenging of the cylinder continues for 30 the remainder of the outstroke of the piston and for a short interval during the instroke, that is until such time that the transfer slots are closed by the piston on the instroke. Shortly after the transfer slots have been closed by the piston on the instroke air is 35 admitted to the lower end of the cylinder through the inlet passages 30 of the short sleeve. The exhaust ports next close and the air remaining in the upper end of the cylinder is compressed during the remainder of 40 the instroke of the piston and the charge of oil is also injected into the cylinder against the air pressure. The air inlet ports do not again close until the piston has again started on the outstroke after a further 45 charge has been exploded in the upper end of the cylinder. This completes the cycle of operation which is continued as long as the engine is running. By admitting the compressed fresh air into the upper end of the 50 cylinder at a plurality of points around the piston and concurrently opening the exhaust ports which are disposed around the cylinder a very effective and complete scavenging is provided.

55 Now that the operation of the engine has been explained the action of the rectangular frame 47 will be better understood. With the link 49 controlling the outer sleeve and in the position shown in Fig. 1 of the drawings I have shown the exhaust valves closed 60 when there is a considerable portion of the instroke to complete while if the link 52 is controlling the sleeve and is in the position shown in Fig. 6 of the drawing the exhaust

valve closes at a later time in the stroke. In 65 the latter case which I term the throttle position I have a much better scavenging than in the first case. This is an important feature as most engines run throttled.

I wish here to explain that the quantity 70 of oil injected into the engine by the pump will require to be controlled by the governor previously mentioned in such a way that the richness of the firing mixture will not vary 75 whether the engine be running at open or throttled position. I wish to point out that the engine could be modified to avoid the use of a cross head.

What I claim as my invention is:—

1. The combination with a suitably mounted crank case, a crank shaft mounted in the crank case, a cylinder secured to the crank case and provided at the one end with suitable air inlet openings and at the other end with suitable exhaust ports, of a valve sleeve 80 85 slidably mounted in the cylinder and provided at one end with air inlet openings designed to register with the aforesaid air inlet openings and at the other end with exhaust ports designed to register with the exhaust ports and having transfer slots appearing on the inner wall thereof, means for reciprocating the sleeve to effect the opening and closing of the air inlet openings and the exhaust ports, and a piston 90 95 slidably mounted within the sleeve and connected to the crank shaft, said piston being arranged to be spanned by the transfer slots in the outstroke thereof, as and for the purpose specified. 100

2. The combination with a suitably mounted crank case, a crank shaft mounted in the crank case, a cylinder secured to the crank case and provided at the one end with suitable air inlet openings and at the other end with suitable exhaust ports, of a valve sleeve 105 110 slidably mounted in the cylinder and provided at the one end with air inlet openings designed to register with the aforesaid air inlet openings and at the other end with exhaust ports designed to register with the exhaust ports and having transfer slots appearing on the inner wall thereof, means for reciprocating the sleeve to effect the opening and closing of the air inlet openings and the 115 exhaust ports, a piston slidably mounted within the sleeve and connected to the crank shaft, said piston being arranged to be spanned by the transfer slots in the outstroke thereof, and means for varying the 120 stroke of the sleeve, as and for the purpose specified.

3. The combination with a suitably mounted crank case, a crank shaft mounted in the crank case, a cylinder secured to the crank case and provided at the one end with suitable air inlet openings and at the other end with suitable exhaust ports, of an outer 125

valve sleeve slidably mounted in the cylinder and provided at the one end with air inlet openings designed to register with the aforesaid air inlet openings and at the other 5 end with exhaust ports designed to register with the exhaust ports and having transfer slots appearing on the inner wall thereof, means for reciprocating the sleeve to effect the opening and closing of the air inlet 10 openings and the exhaust ports, an inner valve sleeve slidably mounted within the outer sleeve and provided with air inlet valve ports designed to register with the air inlet ports, means for reciprocating the inner valve sleeve to control the admission of air through the inlet openings to the lower 15 end of the cylinder, a piston slidably mounted in the outer sleeve and means connecting the cylinder with the crank shaft, said piston 20 being arranged to be spanned by the transfer slots in the working stroke thereof, as and for the purpose specified.

4. The combination with a crank case and a crank shaft mounted in the crank case, of 25 a cylinder mounted on the crank case and fitted at the one end with suitable air inlet openings and at the other end with suitable exhaust ports and provided at the former end with a head carrying an extending short 30 sleeve contained within the cylinder, an outer sleeve slidably mounted in the cylinder and provided at one end with air inlet openings and at the opposite end with exhaust ports and having the inner wall thereof fitted with transfer slots, means for reciprocating the sleeve to effect the registration of the respective inlet openings and the respective exhaust ports, an inner sleeve 35 slidably mounted within the outer sleeve and contained between the outer sleeve and the short sleeve of the cylinder head, said inner sleeve being fitted with air inlet openings, means for reciprocating the inner sleeve to control the time of admission of air through 40 the inlet openings to the lower end of the cylinder and a piston slidably mounted within the outer sleeve and connected with the crank shaft through the head, said piston being designed to be spanned by the transfer slots in the working stroke thereof, as and for the purpose specified.

5. The combination with a crank case and a crank shaft mounted in the crank case, of 55 a cylinder mounted on the crank case and fitted at the one end with suitable air inlet openings and at the other end with suitable exhaust ports and provided at the former end with a head carrying an extending short sleeve contained within the cylinder, an outer sleeve slidably mounted in the cylinder and provided at one end with air inlet openings and at the opposite end with exhaust ports and having the inner wall thereof fitted with transfer slots, an eccentric mount- 60

ed on the crank shaft and connected through 65 a suitable link with the outer sleeve, said eccentric controlling through the sleeve the registration of the respective inlet openings and the respective exhaust ports, an inner sleeve slidably mounted within the outer sleeve and contained between the outer sleeve and the short sleeve of the cylinder head, said inner sleeve being fitted with air inlet openings, an eccentric mounted on the crank shaft and connected with the inner sleeve, 70 said latter eccentric controlling the admission of air through the inlet openings to the lower end of the cylinder and a piston slidably mounted within the outer sleeve and connected with the crank shaft through the 75 head, said piston being designed to be spanned by the transfer slots in the working stroke thereof, as and for the purpose specified.

6. The combination with a crank case and 80 a crank shaft mounted in the crank case, of a cylinder mounted on the crank case and fitted at the one end with suitable air inlet openings and at the other end with suitable exhaust ports and provided at the former 85 end with a head carrying an extending short sleeve contained within the cylinder, an outer sleeve slidably mounted in the cylinder and provided at one end with air inlet openings and at the opposite end with exhaust 90 ports and having the inner wall thereof fitted with transfer slots, a pair of eccentrics mounted on the crank shaft, links connected to the eccentrics, a rectangular frame carried by the links, means connecting the outer sleeve slidably with the rectangular frame, said eccentrics controlling through the sleeve the registration of the respective inlet openings and the respective exhaust ports, an inner sleeve slidably mounted within the outer sleeve and contained between the outer sleeve and the short sleeve of the cylinder head, said inner sleeve being fitted with air inlet openings, an eccentric mounted on the crank shaft and connected with the inner sleeve, said latter eccentric controlling the admission of air through the inlet openings to the lower end of the cylinder and a piston slidably mounted within the inner sleeve and connected with the 100 crank shaft through the head, said piston being designed to be spanned by the transfer slots in the working stroke thereof, as and for the purpose specified.

7. The combination with a cylinder provided with suitable closure heads and having air inlet openings located in one end thereof and exhaust ports located in the other end thereof, of a reciprocating sleeve contained within the cylinder and supplied 105 with corresponding inlet openings and exhaust ports and having transfer slots formed in the inner wall thereof intermediate of its

length and a reciprocating piston slidably mounted within the sleeve and arranged to be spanned by the transfer slots in the working stroke thereof and effect a communication between the ends of the cylinder past the piston through the slots, as and for the purpose specified.

Signed at Winnipeg this 15th day of April 1914.

PHILIP PRINGLE.
